[57] CLAIM

The ornamental design for a spoiler, as shown and described.

DESCRIPTION

FIG. 1 is a rear perspective view of a spoiler constructed in accordance with the teachings of the present invention shown operatively attached to a portion of a motor vehicle, it being understood that the broken line showing of the portion of the motor vehicle is for illustration only and forms no part of the subject invention.

FIG. 2 is a top view thereof;

FIG. 3 is a bottom view thereof;

FIG. 4 is a rear side view thereof;

FIG. 5 is a front view thereof; and,

FIG. 6 is a right end view thereof, it being understood that the left side is a mirror image thereof.
